CLAIM

The ornamental design for a bra, as shown and described.

DESCRIPTION

FIG. 1 is a front, right and top perspective view of a bra, showing my new design;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area labeled "9" in FIG. 1; FIG. 10 is an enlarged view of the area labeled "10" in FIG. 2;

FIG. 11 is an enlarged view of the area labeled "11" in FIG. 3; and,

FIG. 12 is an enlarged view of the area labeled "12" in FIG. 8.

The dot-dash broken lines depict the boundaries of the enlargements that form no part of the claimed design.

The dash-dash broken lines shown in the drawings illustrate portions of the bra that form no part of the claimed design.

1 Claim, 12 Drawing Sheets
